UNITED STATES PATENT OFFICE.

VIKTOR GRAFE AND KUNO PECHÉ, OF VIENNA, AUSTRIA-HUNGARY.

PROCESS FOR THE MANUFACTURE OF ALBUMINOUS PRODUCTS FROM THE RESIDUES
OBTAINED IN THE OIL MANUFACTURE.

1.169.634.

Specification of Letters Patent. Patented Jan. 25, 1916.

No Drawing.

Application filed March 23, 1915. Serial No. 16,423.

To all whom it may concern:

Be it known that we, VIKTOR GRAFE, professor of the Vienna University, and KUNO PECHÉ, chemist, subjects of the Emperor of 5 Austria-Hungary, residing at Vienna, Austria-Hungary, have invented certain new and useful Improvements in Processes for the Manufacture of Albuminous Products from the Residues Obtained in the Oil Manufacture, of which the following is a specification.

The object of the present invention is to obtain irreproachable albuminous products for the food industry from the residues of the oil manufacture. For that purpose particularly it is to be aimed to remove thoroughly the oils, sebacic acids and their products of transformation.

It is already known to free from grease the residues of the oil manufacture and then to extract the albuminous materials and to separate them from the extracts by precipitation. In order to remove all fatty matters from the residues till now these were, however, always treated by means of grease-solvents, a treatment by which the object—that is to obtain from the residues of the oil manufacture albuminous materials freed from all substances emitting a smell or taste and from all easily putrescible admixtures—is by no means perfectly attained. That on industrial scale a sufficiently perfect ungreasing of the residues cannot be obtained by means of grease-solvents, is shown already by the fact that meals or flours ungreased by benzin and similar solvents still contain on an average up to 3% of grease. Conformably to this it is also impossible to extract the whole grease by means of ether, when analyzing the oil-cakes; it is, rather, necessary to effect previous to the extraction a complicated digestion of the albumin in order to completely remove the remnants of oil from the cakes. Besides, there can never be removed, by means of grease-solvents, the products of transformation of the fats which have an unfavorable influence upon the taste.

According to the present invention the oils and sebacic acids are removed by saponification or formation of soaps by treating in the warmth the residues of the oil manufacture with alkali (without previous extraction by means of grease-solvents). Hereby the free sebacic acids are combined to soaps,

the oils are saponified, and the other undesirable by-constituents are dissolved. At the same time part of the vegetable proteins also passes into solution, whereas another part remains unsolved in the residue. Now it 60 has been found that by thoroughly neutralizing the soap-solution with acids the dissolved albumin may be separated from the much more constant soaps in a very simple and perfect manner, the soap, namely, remaining undecomposed, whereas the albumin dissolved in the alkaline soap-solution is precipitated, and may be separated from the soap-solution by pressing, flinging off, etc. 65 70

The process is preferably accomplished, as follows: The comminuted residues of the oil manufacture are mixed up with water to a pulp or paste. Then a mixture of alkali carbonate and alkali hydroxid is added and the whole then heated. The greasy admixtures of the most residues of the oil manufacture chiefly consist of free sebacic acids for the transformation of which into soaps the weaker alkali carbonates are sufficiently strong. Besides, according to the nature of the residues a smaller or larger quantity of alkali hydroxid must be employed for the saponification of the oils. Thus, for instance, 100 kgs. of ground arachis-cakes are mixed with 4-5 hectoliters of water to which have been added about 5 kgs. of soda and about 2 kgs. of sodium-hydroxid. Hydroxids may also be used, of course, instead of the carbonates. In order to deodorize and to decolorize the product, there may further be added reducing substances to the mixture, besides the alkali. After having heated the mixture up to the complete saponification of the oils, which usually takes place within 15-20 minutes, it is (preferably without previously separating the soap-solution, containing dissolved a part of the proteins, from the solid parts, containing the undissolved albuminous substances) neutralized by means of acids, "lakmus" being used here as indicator. By the neutralization the albuminous substances dissolved in the alkaline soap-solution are precipitated. Then the liquid part containing the soaps is separated by pressing or the like from the solid parts in which there are now all the albuminous substances whereupon the solid residue is washed first with hot water and then with cold water. In order to carefully remove 11

the soap remnants having been taken with at the precipitation of the albumin it is recommended to wash once more the already water-washed residue and to use for this 5 washing a very diluted cold soda-solution (for instance one of 0.5%) in which solution the albumin is completely insoluble and finally to wash by means of cold water. In that manner a product is obtained which 10 besides the quantitative yield of albumin and the raw fiber also contains part of the ashes whereas the oils, sebacic acids and extractive substances, free from nitrogen, have been removed. This product is odorless and tasteless, slightly colored, and may be used as 15 material for the manufacture of meat-substitutions, etc. From this material rich in albumin there may be obtained a pure albumin, by extracting with lye or salt-solution 20 or by dialysis, whereupon the pure albumin may finally be decomposed into various albuminous preparations.

In accomplishing the invented process one may, however, proceed also in such manner 25 that after the hot treating of the pressed cakes, etc., with alkali the soap-solution is separated immediately (i. e. without previous neutralization), from the solid parts by pressing, flinging off, etc., and that the 30 proteins are then precipitated by neutralizing the flowing off soap-solution. The proteins separated from the soap solution may be treated either apart from or together with the albuminous substances contained in 35 the ungreased residues.

By the invented process the residues of the oil manufacture are freed in a simple and perfect manner from the admixtures of a greasy nature, easily putrescible and have 40 an unfavorable influence upon the taste, and also from other by-constituents objectionable to the taste, the odor and the aspect of the albuminous materials.

With the invented process there may be 45 manufactured, for instance, press residues of the oil manufacture from seeds of cotton, sesame, groundnut, cocoa, sunflower, poppy, madia, niger, pumpkin, candle, capoc, soy and linseed.

We claim:

1. A process for the preparation of albuminous products from the residues remaining in the oil manufacture, consisting in treating in the warmth the residues with alkali for the purpose of saponifying the oil, 50 transforming the free sebacic acids into soaps and eliminating other admixtures 55 objectionable to the taste, the odor and the aspect of the albuminous material, and in precipitating thereupon the albumin dissolved in the alkaline soap-solution. 60

2. A process for the preparation of albuminous products from the residues in the oil manufacture, consisting in treating in the warmth the residues of the oil manufacture with alkali, and in neutralizing, for 65 the purpose of precipitating the proteins dissolved in the soap-solution, the mixture by acids without previously separating the soap-solution, in which a part of the protein is dissolved, from the solid parts containing the unsolved albuminous substances and in separating thereupon the soap-solution 70 from the solid parts, and carefully washing the solid residue. 75

3. A process for the preparation of albuminous products from the residues in the oil manufacture, consisting in treating in the warmth the residues of the oil manufacture with alkali, separating the soap-solution 80 from the solid parts, separating the proteins by neutralizing the soap-solution, and carefully washing the precipitated proteins. 85

4. A process for the preparation of albuminous products from the residues in the oil manufacture, consisting in treating in the warmth the residues of the oil manufacture with alkali, separating the soap-solution from the solid parts, separating the proteins by neutralizing the soap-solution, and treating 90 the precipitated proteins together with the albuminous substances remaining in the ungreased residues. 95

VIKTOR GRAFE.
